LIQUID MEASURING, CAN FILLING
APPARATUSCharles F. Eaton, Methuen, Mass., assignor to
Bennett Incorporated, Cambridge, Mass., a cor-
poration of Massachusetts

Application November 13, 1945, Serial No. 628,012

12 Claims. (Cl. 222—438)

1
The object of this invention is to furnish a machine adapted for use to fill cans rapidly with accurately measured relatively large quantities of liquid; and to thus fill a number of cans simultaneously. I have heretofore invented and disclosed in a patent application filed by me June 29, 1944, Serial No. 542,779, now Patent No. 2,422,719, June 24, 1947, for Can filling machine, a machine preeminently adapted for filling small cans with accurately measured charges in the order of from one fluid ounce to one quart. The apparatus which forms the subject matter of this invention is intended to measure substantially larger quantities of from one quart up to one gallon or more, and deliver the measured quantities into cans.

By way of definition I would say that the word "can" as used in this specification and in the claims is not limited in its significance to rectangular cans made of tin plate, but is intended to include and embrace liquid containers of all characters and shapes, made of any suitable material, unless the context definitely specifies otherwise.

In the accompanying drawings I have shown on a reduced scale a specific apparatus of which the parts have been designed to fill gallon cans with accurately measured gallons of liquid. In these drawings,

Fig. 1 is a front elevation of the apparatus, with omission of the supply tank;

Fig. 2 is an end elevation of the apparatus as seen from the left of Fig. 1 with the supply pipe in section on line 2—2;

Fig. 3 is a fragmentary horizontal section taken on line 3—3 of Fig. 1, with parts below that line shown in plan;

Fig. 4 is a vertical section taken on line 4—4 of Fig. 1 and shown on a larger scale;

Fig. 5 is a fragmentary longitudinal section taken on line 5—5 of Fig. 4;

Fig. 6 is a perspective view of one of the displacers.

Like reference characters designate the same parts wherever they occur in all the figures.

The apparatus comprises a suitable supporting structure which in this instance is constructed of legs 6, 6, a shelf 7 which forms a table whereon cans to be filled are placed, and an upper shelf 8 by which valved delivery spouts and valve operating means are supported and positioned. Parallel angle irons 9 and 10 are mounted on the upper ends of the front and rear legs, respectively, and are disposed with horizontal flanges projecting inwardly as ledges to support the longitudi-

5 nal bottom corners of a tank or casing 11. A cover or roof 12 is supported by the rear wall and one end wall of the casing 11. This cover is formed with a high central longitudinal ridge and steeply pitched sides and has an end wall at one end (that remote from the operator's station), while the other end is open, or may be covered, wholly or partially, by a transparent pane. The lower edges of its rear and end walls are received in a grooved ledge 13 on the upper edges of the corresponding walls of the casing. A slot 14 of sufficient width to admit inflow of air is provided between the lower edge of the front side of the cover and the upper edge of the front 15 wall of the casing. Exhaust conduits 15 may be connected with the ridge of the cover, as shown in Fig. 1, to conduct away vapors arising from the liquid being measured. But this is an optional feature employed when the liquid handled 20 emits noxious fumes. With inoffensive liquids, the natural flow of air through the slot 14 and out from the open end of the cover affords sufficient ventilation.

The operator's station is at the left hand end of 25 the apparatus with respect to Fig. 1, that is, the end through which he can see into the interior. Thus the operator may observe the flow of liquid into and out of the measuring vessels. Shielded fluorescent lighting tubes 16 are mounted outside 30 of translucent panes set into one wall of the cover for illuminating the interior of the casing.

Measuring vessels 17 are mounted in a row on the bottom and along the front wall of the casing 11, with a wide enough spacing between their 35 central points to permit placement of a can to be filled beneath the outlet of each. They are open at the top and each has an outlet opening in its bottom registering with an opening in the bottom of the casing through which a tubular nipple or pipe section 18 extends. Each nipple 18 passes downward into connection with a stop valve casing 19, which rests on the shelf 8 and is secured thereto by a tube section 20 screwed into the lower end orifice of the valve casing, 40 passing through the shelf, and having a lock nut 21 screwed on its lower end.

A supply tank for liquid, not here shown, is supported at a level somewhat higher than the casing 11 and in it the liquid to be dispensed is 45 maintained at a substantially constant level, preferably, in order that the time required to fill the measuring vessels 17 will be uniform. A pipe 22 leads from the supply tank into connection with a horizontal distributing pipe 23, which 50 extends from end to end in the housing 11 and

is rotatably mounted in bearings in the end walls thereof at a height above the tops of the measuring vessels 17.

Nozzles or delivery tubes 24 project from the distributing pipe 23 in a longitudinal row from one side thereof and are spaced apart on centers equally to the center spacing between the several measuring vessels. They are located in the same planes, transverse to the pipe 23, with some part of the spaces embraced by the bounding walls of the several measuring vessels, and each is of a length approximately equal to, or slightly more than, the distance from the pipe to the upper end of the nearest measuring vessel, and less than the distance from the pipe to the front wall of the casing; the measuring pipe being set back from such wall more than midway of the casing. These parts are so arranged that the distributing pipe and delivery nozzles can be placed in the position shown by full lines in Figs. 4 and 5, where the nozzles project upwardly and rotated thence to the position shown by broken lines in Fig. 4, in which the nozzles are in delivering relation to the measuring vessels. A hand crank 25 is secured to the end of the distributing pipe which projects adjacent to the operator's station and serves the operator for rotating the pipe back and forth between these positions. Stops 26 and 27 projecting from the adjacent bearing of the pipe, (and the angular spacing of which around the axis is best shown in Fig. 2), arrest the crank in one or the other, respectively, of these positions.

The distributing pipe is connected with the end 22a of the supply pipe by a swivel coupling 28 of any character suitable to permit easy enough rotation while preventing leakage. A valve (hereinafter referred to as the delivery valve) is associated with the crank and controlled thereby to permit flow of liquid when the pipe and nozzles are in the delivering position, (broken line position of Fig. 4), and shut off the flow when the nozzles are in the other position. Any one of a number of valves and valve operating means may be used for this purpose. The one illustratively shown herein comprises a housing 29, connected in the pipe line 22 adjacent to the crank 25, in which a gate is mounted by means of a pivot 30 to swing back and forth across the passageway through the valve housing. An external arm 31 is connected to pivot 30 and is biased by a spring 32 so as normally to hold the valve gate in closed position. Arm 31 is located in the path of a pin 33 which projects from the crank arm and is so disposed that, when the crank is in stopped engagement with the stop pin 21, arm 31 is displaced so as to open the valve gate widely, (the nozzles being then in position to deliver liquid into the measuring vessels). When the crank is withdrawn from stop 27, the valve gate is closed by spring 32. The valve gear above described is intended to typify any means for performing the essential functions of turning on and off the flow of liquid conformably with positions of the delivery nozzles. The details of the delivery valve are of minor importance provided it performs these functions.

A shut down valve 34 is located in the pipeline in advance of the delivery valve for the purpose of closing off the supply when the apparatus is left idle over night or for any other long-extended period. It is of a tight closing character to prevent any possible leakage and dripping of the liquid.

In order to insure accurate measurement of

liquid volume by the vessels 17, the nipples 18 project far enough above the bottoms of the vessels to retain enough liquid to cover their bottoms after each discharge of their contents. The level of the liquid thus retained establishes a definite and invariable level for the bottom of the charge at each filling. The top level of the charge is determined by a part 35 of the upper edge which is at a lower level than all other parts of the upper edge. The level of part 35 is set by any suitable method so that the quantity of liquid between the level which it establishes and the level established by the retained liquid in the bottom of the vessel is somewhat more than the amount required to be placed in the cans being filled. In order to give an exact adjustment of quantity I have provided a displacer 36 in association with each measuring vessel so mounted that it can be adjusted up and down in the upper part of the vessel. One of such displacers is shown in Figs. 4 and 6. It is secured to a slotted strap 36a which is held against the front wall of the casing 14 by a threaded stud projecting from the wall through the slot of the strap and a wing nut screwed on the stud. By adjusting the displacer so as to extend more or less deeply into the measuring vessel, the interior of the latter available for reception of liquid may be instantly varied within exceedingly narrow limits of accuracy. As a convenient manufacturing detail, the displacers are made as sheet metal boxes open at the top and are filled with the liquid being measured so as to have no buoyancy.

The vertical distance between the table 7 and shelf 8 is made such as to permit placement of standard cans of the prescribed capacity on the table with their spouts or nozzles directly beneath the outlet of the delivery connections formed by the nipple 18, valve casing 19 and coupling thimble 20. Gages 37 are secured to the upper side of the table, suitably formed to embrace the bottom ends of cans and locate a can in alignment with each one of these delivery connections. Cans 38 are here shown as supported on the table and located by the gages in a row parallel to the row of measuring vessels with their several spouts or nozzles 39 in register with the several delivery connections.

Valve bodies 40 are mounted rotatably in the valve casing 19 and are so constructed that by a partial rotation in one direction or the other they open wide or wholly obstruct the delivery passages. All the valve bodies are connected by sprocket and chain gearings 41 with a shaft 42, which is mounted in bearing brackets 43 on the shelf 8. A crank arm 44 is secured to the shaft at the end of the machine where the operator takes his station. Stops 45 and 46 are situated in the path of a lug 47 on the hub of the crank arm suitably to arrest the arm when the valves are, respectively, in the closing and opening positions. The valves 19-40 are provided to prevent discharge from the measuring vessels while they are filling up. An overflow discharge conduit 48 leads from the bottom of the casing to conduct away the liquid which overflows from the measuring vessels when they are full.

In the use of this apparatus the operator takes a position at the end of the machine where the cranks 25 and 44 are located and whence he can look into the casing through the near end of the cover. The cranks are accessible to his two hands so that he can operate them in alternation. Before filling the measuring vessels he closes the outlet valves thereof by placing the crank 44 in

the position shown in the drawings. He then turns the crank 25 to bring the nozzles 24 into the broken line position shown in Fig. 4, and thereby opens the delivery valve in the supply pipe. When the measuring vessels are full and the liquid spills over their rear edges, he returns the crank 25 and nozzles 24 to the former position, and opens the delivery valves by means of the crank arm 44. Then repeats these operations when the flow from the measuring vessels has ceased. An attendant removes the filled cans and places empty ones in the positions established by the gages 31.

It will be noted that the position of the distributing pipe 23 is far enough in rear of the front wall of the casing to permit unobstructed swinging movement of the nozzles and that the outlet ends of the nozzles are arrested at the rear of the measuring vessels when brought to the raised stopping position. This arrangement prevents any dripping of the liquid into the measuring vessels after the nozzles have been brought upward. If any leakage through the valve 29 occurs then, the resulting drip falls to the bottom of the casing outside of the measuring vessels and is discharged through the overflow conduit. This factor cooperates with the characteristics of the measuring vessels, previously described, to insure delivery of accurately measured equal quantities in each can filling cycle.

It is possible to establish the lowest point of the upper edge of the measuring vessels at such a height that the volume between the level thereof and the bottom level is exactly that of the liquid required to be filled into the cans, and when that condition is established, it is possible to do without the displacers. However, the displacers are an important feature, because their use enables the measured volumes to be exactly regulated more easily than is possible by calibration of the overflow edge; and they have the additional utility of enabling the volume to be varied instantly and without disturbing any other part of the machine, whenever it may be necessary to increase or diminish the measured quantities to meet varied conditions.

What I claim is:

1. A liquid measuring can filling apparatus comprising a casing adapted to hold liquid, a measuring vessel fixed in position within said casing having a delivery outlet leading from its bottom through the bottom of the casing, a shiftable spout in connection with a supply of liquid arranged for placement in a position where it delivers liquid into the top of the measuring vessel and into another position where its outlet orifice is clear of the measuring vessel, and a valve in said outlet operable to close the outlet when the measuring vessel is being filled and to open the outlet for delivery of liquid.

2. A multiple can filling apparatus comprising a casing having a substantially horizontal bottom, a plurality of measuring vessels mounted side by side in a row on said bottom having overflow edges at their upper ends, valved outlet connections from the bottoms of the measuring vessels, a distributing pipe extending parallel to the row of measuring vessels at a level above the tops thereof, nozzles projecting from said pipe in a row along one side thereof with spacing between them conforming to the positions of the several measuring vessels, a supply source connected with said pipe for supplying liquid thereto, the pipe being rotatable to place said nozzles in a position wherein they are adapted to deliver liquid into the vessels, and in a second po-

sition where their outlet ends are moved from the vessels, and a valve operable concurrently with rotational movements of the distributing pipe for admitting liquid thereto from the supply source when the nozzles are in the first named position and shutting off the flow when the nozzles are in the second position.

3. A liquid measuring and delivering apparatus comprising a casing having a substantially 10 level bottom, a substantially horizontal pipe mounted in the upper part of the casing extending lengthwise thereof and being rotatable about its axis, nozzles projecting from said pipe arranged in a longitudinal row at one side of the pipe and being shiftable by rotation of the pipe from a position in which they project upwardly to one in which they project downwardly, measuring vessels mounted on the bottom of the casing in a row parallel to said pipe with a spacing 15 corresponding to that of said nozzles in positions enabling each to receive liquid issuing from one of the nozzles when the pipe is turned to bring the nozzles into the before named downwardly projecting position, means for supplying liquid 20 to said pipe, and means for delivering liquid from the several measuring vessels.

4. In a liquid measuring apparatus of the character set forth, a measuring vessel mounted in a stationary position having a valve controlled discharge outlet in its bottom and an 30 overflow edge at its open top, a supply pipe having a nozzle rotatably mounted to bring such nozzle into position for passing liquid into the measuring vessel and into another position 35 wherein it is displaced from the vessel, and a valve operable to admit liquid into the supply pipe when in the first named position, and exclude liquid therefrom when in the second named position.

5. In a liquid measuring apparatus of the character described, a plurality of measuring vessels arranged side by side in a substantially horizontal row having valve controlled outlets from their bottoms and overflow edges at their upper 40 ends, a distributing pipe horizontally mounted in parallel with the row of measuring vessels having spouts projecting from one side located in the same planes transverse to the pipe with the several vessels, means for rotating said pipe to 45 bring the nozzles into and out of position for passing liquid into the receptacles, and a supply pipe leading to the distributing pipe and with which the latter has a packed swivel connection.

6. A liquid measuring apparatus comprising a 50 plurality of measuring receptacles mounted in stationary locations side by side in a substantially horizontal row, valves mounted beneath the several measuring receptacles in liquid receiving and passing connection therewith, a shaft 55 rotatably mounted adjacent to said valves, transmission gearing between the shaft and all of said valves for opening or closing the latter simultaneously when the shaft is rotated in one direction or in the opposite direction, a crank connected to said 60 shaft for rotating it, a distributing pipe having laterally projecting nozzles mounted rotatably with provision for placing the several nozzles thereof in delivering relation to the several measuring vessels, and removing the nozzles from the 65 vessels, a supply connection leading to said delivery pipe, and a crank connected to said pipe for rotating it, both cranks being located at one 70 end of the apparatus for manipulation by a single operator.

7. In a liquid measuring apparatus of the char-

acter set forth, a measuring vessel open at its top mounted in a stationary position having a valve-controlled discharge outlet in its bottom and an overflow edge in its top, and a displacer mounted for adjustment to extend more or less deeply into the upper end of the vessel, whereby to calibrate the internal liquid-receiving volume of the vessel, a supply conduit having a nozzle mounted revolvably so as to bring the outlet of the nozzle into position for delivering liquid into the vessel and into another position wherein it is displaced from the vessel, and a valve operable to admit liquid to said nozzle when in the first position and exclude liquid therefrom when in the second position.

8. In a liquid measuring apparatus of the character described, a plurality of measuring vessels open at their tops and arranged side by side in a substantially horizontal row, having valve-controlled outlets from their bottoms and overflow edges at their upper ends, displacers mounted in association with the several measuring vessels for adjustment more or less deeply in the tops of the vessels, a distributing pipe horizontally mounted in parallel with the row of measuring vessels having nozzles projecting from one side located in the same planes transverse to the pipe with the several vessels, means for rotating said pipe to bring the nozzles into and out of position for delivering liquid into the receptacles, and means for operating the controlling valves of the outlets in the bottoms of the vessels.

9. A liquid measuring and delivering apparatus comprising a casing having a bottom and an outlet leading from its lower portion, a measuring vessel mounted in the casing having an outlet from its bottom leading through the casing bottom, and having an overflow edge in its upper part so arranged that liquid entering the vessel in excess of the amount necessary to raise the liquid level up to said edge can spill over the edge into the bottom part of the casing, means for conducting liquid into said casing having a discharge portion shiftable between a position wherein it can deliver liquid to the measuring vessel, and into another position wherein its discharge is received by the casing outside of the measuring vessel, and valve means controlling the outlet from the measuring vessel.

10. In a liquid measuring apparatus of the character set forth, a measuring vessel mounted in a stationary position having a valve-controlled discharge outlet in its lower portion and an overflow edge in its upper portion, a rotatably mounted supply pipe having a laterally projecting nozzle arranged to be placed by rotation of the pipe in position to pass liquid into the measuring vessel and into another position where its delivery point is displaced from the entrance to the vessel, a

valve element located for movement to obstruct and open the passage through the pipe alternately, and means controlled by the pipe in its rotation for causing said valve element to open the pipe passage when the nozzle is in the first of the above named positions and to obstruct the passage when the nozzle is in the second of said positions.

11. In a liquid measuring apparatus of the character described, a rotatably mounted supply pipe having a nozzle extending from its side and arranged to be placed, by rotation of the pipe, in one position where it is upwardly directed and in another position where it is downwardly directed, a valve housing connected with said pipe for passage through it of liquid entering the pipe and containing a movable passage closing element, a pivot rotatable in opposite directions to cause actuation of the valve element to obstruct and open said passage, respectively, means operable simultaneously with rotation of said pipe to turn said pivot into the valve closing position when the nozzle is raised and into the valve opening position when the nozzle is lowered, and a measuring vessel having a valve controlled delivery outlet and an overflow, arranged to receive liquid from the nozzle when the latter is in its lowered position.

12. A liquid measuring apparatus comprising a casing, a measuring vessel in said casing having an open top with an overflow edge located where it can be seen by an operator at a control station adjacent to the casing, a pipe entering the casing and mounted so that it can be rotated by an operator at such station, said pipe having a delivery nozzle movable by rotation of the pipe into a position where it can discharge into the receiving opening of the measuring vessel, and to another position where any liquid discharged from it will lodge in the casing without entering the vessel, and a valve operable by an operator at such station for closing and opening the outlet of the measuring vessel.
